UNITED STATES PATENT OFFICE.

HENRY W. McNEIL, OF SINTON, TEXAS.

GEARING.

1,157,167.

Specification of Letters Patent.

Patented Oct. 19, 1915.

Application filed October 25, 1912. Serial No. 727,698.

To all whom it may concern:

Be it known that I, HENRY W. McNEIL, a citizen of the United States, residing at Sinton, in the county of San Patricio and State 5 of Texas, have invented certain new and useful Improvements in Gearing, of which the following is a specification.

My invention relates to gearing, and particularly for machines for washing clothes 10 and the like.

The object of my invention is to provide a simple, cheaply constructed and efficient machine of this type.

I have illustrated an embodiment of my 15 machine in the accompanying drawing, in which:

Figure 1 is a side elevation of my invention showing the tub or boiler in cross section. Fig. 2 is a top plan view of the same. 20 Fig. 3 is a side elevation of a modification of my invention partly broken away. Fig. 25 Fig. 4 is a top plan view of the same.

Reference character 1 designates a clothes receptacle which is preferably of semi-circular shape and is mounted over a suitable 25 furnace 2 for heating the water, maintaining the water in heated condition while the machine is being operated, or boiling the clothes, as desired. The tub 1 is provided with a drainage pipe 3 provided with a 30 faucet 4.

The tub 1 is fitted with a removable cover 5 on which is mounted the washing mechanism of the machine as follows: A base plate 35 6 is secured to the cover 5 at approximately the center thereof. Mounted on the base plate 6 is a pair of parallel standards 7, which are connected at their upper ends by a cross-bar 8. Journalled in bearings in the 40 cross-bar 8 and base-plate 6 and extending through a corresponding aperture in the cover 5 is a vertical shaft 9. The shaft 9 is provided at its lower free end with a dolly 10. The base plate 6 is provided at each 45 side thereof with set-up bearings 11 in which is journaled a crank-shaft 12. One end of said shaft 12 is elongated and journaled, near the outer edge of the cover 5, in a bracket bearing 13. The shaft 12 is pro-

vided at its outer free end with a crank 50 wheel 14. The shaft 12 is provided with two crankpins 15 symmetrically disposed with relation to the standards 7. A reciprocating member 16 is slidingly mounted on the standards 7, at right angles thereto, said 55 member 16 being provided with a centrally disposed collar 17 provided with two inwardly projecting pins 18 which engage respectively two spiral grooves 19 on said shaft 9. A pair of connecting rods 20 are 60 mounted at one end on the crank pins 15 and at the other end are connected to the reciprocating member 16.

It will be obvious that when the crank wheel 14 is rotated, the member 16 will be 65 reciprocated vertically on the standards 7, and the pins 18 traveling in the grooves 19 will rotate the shaft 9 in one direction during the upward stroke of the member 16 and in the opposite direction during the downward stroke of the member 16. The shaft 70 9 communicates a corresponding rotation to the dolly 10, first in one direction and then in the other.

Figs. 3 and 4 illustrate my invention applied to an ordinary clothes tub without the furnace. The construction of the washing mechanism is the same.

It is to be understood that I contemplate 75 any variations in construction which come within the scope of the appended claim.

What I claim is:

In a device of the character described, the combination with a support, of a crank shaft mounted upon said support adjacent 85 to the surface thereof, means for imparting rotation to said crank shaft, standards mounted upon said support, a cross-piece slidably engaging the free end portions of said standards, connecting rods, each having 90 one of its extremities engaged by said crank shaft and the other by said cross-piece, a dasher shaft rotatably supported by and traversing said support and provided with spiral depressions upon its curved surface, 95 a collar integrally supported by said cross-piece and traversed by said dasher shaft and means integrally projecting from and

supported by said collar and engaging said spiral depressions effecting rotation of said dasher shaft upon sliding displacement of said collar longitudinally of said dasher shaft, all arranged so that continuous rotation of said crank shaft imparts reciprocating rotation of said dasher shaft.

In testimony whereof I have signed my name to this specification in the presence of two subscribing witnesses.

HENRY W. McNEIL.

Witnesses:

J. L. ALLEN,
E. W. McGLOIN.
